UNITED STATES PATENT OFFICE

EDWARD S. PRESTON, OF CHICAGO, ILLINOIS, ASSIGNOR TO CHICAGO ELECTRIC MANUFACTURING CO., OF CHICAGO, ILLINOIS, A CORPORATION OF ILLINOIS

DESIGN FOR AN ORANGE JUICE EXTRACTOR

Application filed January 9, 1933. Serial No. 46,776. Term of patent 7 years.

To all whom it may concern:

Be it known that I, EDWARD S. PRESTON, a citizen of the United States, residing at Chicago, in the county of Cook and State of Illinois, have invented a new, original, and ornamental Design for an Orange Juice Extractor, of which the following is a specification, reference being had to the accompanying drawing, forming part thereof.

In the drawing, Fig. 1 is a perspective view of an orange juice extractor, showing my new design.

Fig. 2 is a plan view of the same.

I claim:

The ornamental design for an orange juice extractor, substantially as shown.

EDWARD S. PRESTON.
